UNITED STATES PATENT OFFICE

FERDINAND W. HAHN, OF MICHIGAN CITY, INDIANA, AND JOHN A. LAMONT, OF CHICAGO, ILLINOIS, ASSIGNEES, BY MESNE ASSIGNMENTS, TO GENERAL STEEL CASTINGS CORPORATION, OF EDDYSTONE, PENNSYLVANIA, A CORPORATION OF DELAWARE

UNDERFRAME

Application filed March 10, 1930. Serial No. 434,510.

The invention relates to railroad rolling stock, and consists in an improved construction of underframe for railway vehicles and primarily for that type known as tank cars.

An object of the invention is to provide an underframe for association with cars of the above type which will employ as a substitute for the center sills a single member so shaped as to utilize the space defined by the usual vertical members of the center sill.

Another object is to provide an underframe for tank cars employing a cast one piece member which will constitute the bottom plate of the tank and also form a substitute for the usual spaced center sills.

Yet another object is to provide an underframe for tank cars employing a cast one piece member forming the bottom plate of the tank which will be so shaped as to increase the space available for carrying the contents.

A further object is to provide an underframe for tank cars which will serve to increase the cubic capacity of the tank and at the same time lower the center of gravity thereof, thus resulting in corresponding saving in manufacturing costs and an increase in simplicity and rigidity of structure.

With these and various other objects in view, the invention may consist of certain novel features of construction and operation as will be more fully described and particularly pointed out in the specification, drawings and claims appended hereto.

In the drawings, which illustrate an embodiment of the device and wherein like reference characters are used to designate like parts—

Figure 1 is a top plan view of the underframe of the present invention showing the one piece longitudinal member secured to the bolster and the end frame;

Figure 2 is a side elevation of the same, parts being shown in cross section;

Figure 3 is an end elevation of the same;

Figure 4 is a fragmentary side elevation of a portion of the underframe structure showing the fluid outlet and steam inlet ports;

Figure 5 is a cross sectional view taken substantially along line 5—5 of Figure 1, and showing the draft gear retaining sills;

Figure 6 is a cross sectional view taken substantially along line 6—6 of Figure 1;

Figure 7 is a cross sectional view taken substantially along line 7—7 of Figure 1;

Figure 8 is a cross sectional view along line 8—8 of Figure 4.

The improved under frame forming the supporting structure for tank cars comprises the usual end sill member 10 having integral side members 11 braced by integral braces 12, the side members being connected to a transversely extending bolster member 13. This end structure is also braced by corner braces 14 and has cast integral therewith striking blocks 15, a carrier iron 16 and push pole pockets 17. The bolster 13 is formed as an integral part of a centrally disposed longitudinal member 20 having a bottom portion 21 and vertical side walls 22, which member extends from end to end of the car and forms the bottom plate of the tank car and also serves as a substitute for the usual center sills. The member is subjected to a uniformly distributed hydrostatic pressure due to the fluid contents of the tank, and is therefore braced to hold the side walls in position by cross ties 19. The bottom portion 21 and side walls 22 form a compartment or well, thus providing an increase in available space for the carrying of fluids in the tank and increasing the cubic capacity thereof, while at the same time lowering the center of gravity of the contents of the whole. This well portion terminates at the walls 23 of the bolster member 13, and wall 24 forms the bottom of the tank over the bolster member, and the usual draft sills, the latter being designated 18. The bolster 13, in addition to the vertical wall 23, is provided with a similar wall 25 spaced therefrom and extending the full length of the member.

It is to be understood that the construction above described and illustrated in Figure 1 forms the end structure of the underframe and is duplicated at both ends of the car. It is seen then, that the well portion of the member 20 is defined at either end by the walls 23 of the bolster and the member continued over the bolster by the bottom walls 24.

The bottom wall 21 of the longitudinal

member 20 has cast integral therewith the brake supporting parts designated as 26, 27 and 28, and is also provided with a draining opening 30 which consists of a separate member 31 threaded as desired and welded in place within an opening provided for the purpose in the bottom member. A steam connection 32 is similarly provided for introducing steam into the tank for heating the contents, such as crude oil, to induce a more rapid flow in cold weather. The arrangement for providing cross-overs for the drain pipes 33 comprises a channel-like compartment including walls 34 which are spaced in parallel arrangement with each other and are supported from the cross ties 19. Brackets 35 are provided at each end of the channel compartment which serve to secure the pipe 33 in position. It is understood that the construction need not be limited to this form of cross-over, as the same may assume merely the form of a pipe extending diagonally of the cross ties 19 and integrally joined to the side walls 22 and provided with flanged ends for connection with the usual drain pipe.

The longitudinally extending member 20 has also integrally formed thereon on the outside of the walls 22 brackets designated 36 which are located at intervals between the bolster and provide the supporting means for the longitudinally extending floor boards 37. For this purpose the brackets 36 have riveted or otherwise secured to them a horizontal brace 38 and an upwardly extending brace 39. The running boards 37 are located on each side of the tank and are supported at their ends by the bolster and at intermediate points between by the braces 39. The member 20 provides the bottom plate of the tank and is adapted to have the remaining tank structure secured thereto. The end portions 40, Figure 2, are secured by riveting or other suitable means to a raised part 41 of the member 20 provided for the purpose. The side sheets 42 are secured in a similar manner to the side portions of the member 20. The construction, however, is not limited merely to riveting the members together, as it is possible to machine the overlapping parts and weld the same, which would be in addition to the rivets. It is also contemplated to extend the brackets 36 upward beyond the riveted joint, in which case the brackets would be riveted to the side sheets 42. This construction allows the brackets to assume some of the strain induced by the lateral movements of the liquid contents.

It is to be understood that we do not wish to be limited by the exact embodiment of the device shown, which is merely by way of illustration and not limitation, as various and other forms of the device will of course be apparent to those skilled in the art with-

out departing from the spirit of the invention or the scope of the claims.

We claim:

1. In a tank car, in combination with end frames, bolsters secured thereto, a longitudinally disposed member joining said bolsters and integral therewith, a well portion formed in said longitudinal member, said member forming the bottom portion of a tank with remaining tank structure secured thereto. 75

2. In a tank car, in combination with end frames, bolsters secured thereto, a longitudinally disposed member joining said bolsters and integral therewith, a well portion formed in said longitudinal member and extending 80 the length between said bolsters, and tank structure secured thereto.

3. In a tank car, in combination with end frames, bolsters secured thereto, a longitudinally disposed member joining said bolsters 85 and integral therewith, said member being formed with vertical walls and a bottom wall, side walls extending the length of said member and joining said vertical walls, and tank structure secured to said side walls, whereby 90 the longitudinal member forms the bottom of said tank.

4. In a tank car, in combination with end frames, bolsters secured thereto, a longitudinally disposed member joining said bolsters 95 and integral therewith, a well portion formed in said longitudinal member between said bolsters, comprising vertical walls and a bottom wall, side walls extending the length of said member and joining said vertical walls, 100 and tank structure secured to said side walls, whereby the longitudinal member forms the bottom of said tank.

5. In an underframe for tank cars, in combination with tank structure, bolsters at each 105 end thereof, a longitudinally disposed casting joining said bolsters and integral therewith, said casting being formed with a depressed portion or well, and comprising the bottom plate for said tank. 110

6. In an underframe for tank cars, in combination with tank structure, bolsters at each end thereof, a longitudinally disposed casting joining said bolsters and integral therewith, the portion of said casting extending centrally thereof and confined between the bolsters being depressed to form a well, the tank structure being secured to the sides of said casting, whereby the casting forms the bottom plate. 115

7. In an underframe for tank cars, in combination with tank structures, bolsters at each end thereof, a longitudinally disposed casting joining said bolsters and integral therewith, said casting being formed with 120 vertical walls and a bottom wall extending the length between the bolsters and forming part of the wall of the tank structure, whereby the vertical walls function as center sills. 125

8. In a railway vehicle, an underframe 130

5 casting forming a tank bottom member and having bolsters integrally secured thereto at each end, said casting having a depressed portion extending centrally and between said bolsters, said casting continuing over said bolsters and formed with a raised portion, the ends of the tank being secured to said raised portion and the sides of the tank being secured to the sides of the casting.

10 9. In a railway vehicle, an underframe casting forming a tank bottom member and having bolsters integrally secured thereto at each end, raised portions provided at the ends of said casting, upwardly curved portions 15 provided along the sides of said casting, the ends of the tank being secured to the raised portions and the sides being secured to the curved portions.

10 10. In a railway vehicle, a one piece 20 underframe casting having bolsters formed integrally therewith, superstructure mounted thereon, said underframe casting being formed with curved sides and a depressed central portion functioning as center sills and 25 forming the bottom of a tank, the superstructure forming the sides and ends of said tank.

11. In a railway vehicle, a one piece under- 30 frame casting having bolsters formed integrally therewith, said casting being formed with curved sides and a depressed central portion, cross-overs for drain pipes formed integral with the depressed portion, super- 35 structure secured to the sides, said super- structure and said casting cooperating to form a tank.

12. In an underframe for tank cars, in 40 combination with tank structure, bolsters at each end thereof formed of transversely ex- 45 tending spaced walls, a longitudinally dis- posed casting integrally joined to the lower end of the inner wall of said bolsters, said casting being formed with a depressed por- 50 tion or well extending centrally and between 55 said inner walls, whereby the vertical walls of the casting formed thereby comprise center sills and said inner walls comprise the end walls of said well.

13. In an underframe for tank cars, in 50 combination with tank structure, bolsters at each end thereof formed of transversely ex- 55 tending spaced walls, a longitudinally dis- posed casting integrally joined to the lower end of the inner wall of said bolsters, said casting being formed with a depressed por- 60 tion or well extending centrally and between 65 said inner walls, said casting continuing over said bolsters and formed with a raised portion, the ends of the tank being secured to said raised portion and the sides of the tank being secured to the sides of the casting.

14. In a railway vehicle underframe, bol- 65 sters, and an arcuate web extending between 70 said bolsters and forming the lower portion of a tank and also forming the main longi-

tudinal element of the underframe between said bolsters.

15. In a tank car underframe, a bolster of 75 box shape cross section, the top wall of which bolster forms a part of the car tank bottom and extends beyond the outer vertical wall of said bolster towards the end of the car and forms a suitable flange for mounting the lower end of a tank end plate which is offset from said bolster.

16. In a tank car underframe, spaced bol- 80 sters, an arcuate web extending between said bolsters and forming the main load carrying and force transmitting member between said bolsters, and draft sills extending outwardly from said bolster with their inner ends merging with said web.

17. In a railway vehicle underframe, spaced bolsters, each having a top plate and a vertical plate, a web plate extending be- 85 tween said bolsters and forming a concave recess below the top of said bolsters, a sub- 90 stantially horizontal plate extending outwardly from the top of each bolster toward the ends of the underframe, all of said plates 95 being substantially imperforate and forming the bottom of a tank.

18. In a railway vehicle underframe, spaced bolsters with top walls, and an im- 100 perforate web plate extending between said 105 bolsters and, with said top walls, forming the bottom of a tank, the side edge portions of said plate being located at substantially the same level as said top walls and the intermediate portion of said plate between said 110 bolsters forming a recess extending below the top of said bolsters.

19. In a railway vehicle underframe, a 115 pair of bolsters and an imperforate web adapted to form the bottom of a tank, each 120 bolster top wall forming at least a portion of each of the web end portions, the intermediate portion of said web between said bolsters forming a recess extending below the top of said bolsters, and a surface extending around 125 the sides and ends of said web for mounting superstructure sheets.

20. In a railway vehicle, an underframe in- 130 cluding a web member extending substan- 135 tially from end to end, and superstructure sheets secured to the edges of said web mem- 140 ber and forming therewith a cylindrical tank adapted to transmit all of the buffing and 145 pulling forces applied to the vehicle.

21. A railway vehicle underframe includ- 150 ing spaced bolsters and an imperforate longi- 155 tudinally extending web forming a tank bot- 160 tom plate, the tops of said bolster forming at least a portion of the end portions of said 165 web plate, and the intermediate portion of said web plate between said bolsters forming a recess extending below the tops of said 170 bolsters.

22. A vehicle underframe comprising spaced 175 bolsters and a single web plate constituting 180

the sole member extending between said bolsters.

23. In a railway vehicle, a cylindrical tank structure comprising an underframe and superstructure, a portion of said underframe having a web plate with arcuate side portions of substantially the same contour as the lower portions of said superstructure and secured thereto, said web plate, together with said superstructure, is adapted to transmit all of the buffing and pulling forces applied to said tank structure.

24. A railway vehicle underframe including a web plate extending longitudinally of the underframe and having an arcuate cross section and adapted to transmit all of the longitudinal forces applied to the underframe.

25. In a railway vehicle underframe, spaced bolsters, each having a top plate and a vertical web plate, a web plate extending between said bolsters and forming a concave recess below the top of said bolsters, all of said plates being substantially imperforate and forming the bottom of a tank.

26. In a railway vehicle underframe, a pair of box shaped bolsters having plate-like top members, draft sills extending outwardly from said bolsters and having plate-like tie members, a web plate extending between said bolsters, said bolster and draft sill members and web plate being imperforate and adapted to form the bottom of a tank, said bolster web plate extending from the bolster side walls towards the end of the underframe, and said extending portion merging with the tops of said draft sill members.

27. A railway vehicle underframe having a longitudinally extending web plate adapted to transmit all of the longitudinal forces applied to said underframe.

Signed at Chicago, Illinois, this 4th day of March, 1930.

FERDINAND W. HAHN.
